2 SHEETS—SHEET 2

Figure 4 shows a side view of a door assembly. It features a main door body 21 with a handle 22. A vertical strip 23 is attached to the side of the door. A hinge 28 is attached to the strip 23. A lock 29 is attached to the strip 23. A label 'Fig. 4.' is written below the drawing.

Figure 5 shows a front view of the door assembly. The door body 21 is shown with a handle 22. A vertical strip 23 is attached to the side of the door. A hinge 28 is attached to the strip 23. A lock 29 is attached to the strip 23. A label 'Fig. 5.' is written above the drawing.

BEDPAN

De Merle E. Eckart, Abilene, and John R.
Rosenleaf, Enterprise, Kans.

Application November 26, 1948, Serial No. 62,114

6 Claims. (Cl. 4—112)

1

The present invention relates to a bed pan, and more particularly to a device intended to be normally supported beneath a hospital bed upon suitable means whereby it may be projected upwardly through an opening in the mattress and into use position. The primary object of the invention is to provide a novel form of bed pan so constructed that, when supported in the manner above defined, and when projected into use position, it will substantially conform to, and lie substantially in contact with, the pelvic floor and the dorsal region of the trunk of a patient on the mattress, whereby the evacuating functions of the body may be accomplished with a maximum of convenience and a minimum of discomfort to the patient. More particularly, the bed pan of the present invention is so designed that the patient, whether supine or slightly elevated, may rest comfortably upon the mattress during the evacuation processes, while being assured that ejected material will be effectively received by the bed pan. It is a further object of the invention to provide a structure whereby colonic material may be ejected in a direction substantially parallel with the surface of the mattress upon which the patient is supine, and will be properly received in the bed pan upon such ejection. Further objects of the invention will appear as the description proceeds.

To the accomplishment of the above and related objects, our invention may be embodied in the forms illustrated in the accompanying drawings, attention being called to the fact, however, that the drawings are illustrative only, and that change may be made in the specific constructions illustrated and described, so long as the scope of the appended claims is not violated.

Fig. 1 is a plan view, more or less diagrammatic, of a portion of a human body in supine position with our bed pan in position of use;

Fig. 2 is a sectional view taken substantially on the line 2—2 of Fig. 1;

Fig. 3 is a perspective view of the nozzle portion of one form of our invention;

Fig. 4 is a perspective view of a support element;

Fig. 5 is an enlarged, fragmental, vertical sectional view taken substantially on the line 5 of Fig. 4, and looking in the direction of the arrows, and showing portions of a receptacle and a nozzle in assembled relation with the support element of Fig. 4;

Fig. 6 is a perspective view of a modified form of container embodying certain features of our invention; and

2

Fig. 7 is a vertical sectional view somewhat similar to Fig. 2 but showing the container of Fig. 6 in use position.

Referring more particularly to the form of invention illustrated in Figs. 1 to 5, it will be seen that we have shown a mattress 10 provided with an opening 11 through which may be projected a container indicated generally by the reference numeral 12. The opening 11 is so positioned that, when a patient is lying comfortably on the mattress 10, the patient's pelvic floor, indicated by the reference numeral 13, is disposed within a projection of the region defined by the opening 11. The container 12, in the illustrated embodiment of the invention, comprises a receptacle 14 suitably supported upon actuating means indicated generally by the reference numeral 15, and provided with a nozzle portion 16. The receptacle 14 may take any suitable form and may be made of any suitable material, and is preferably valved in accordance with the disclosures of our co-pending application Serial No. 62,113, filed November 26, 1948 for Valved Bed Pan. The actuating mechanism 15 may preferably be of the character disclosed in our co-pending application Serial No. 62,112, filed November 26, 1948 for Bed Pan Device. The opening 11 in the mattress 10 will preferably be constructed in accordance with the disclosures of our co-pending application Serial No. 62,115, filed November 26, 1948 for Mattress.

In the embodiment of the invention illustrated in Figs. 1 to 5 inclusive, the nozzle portion 16 of the container 12 is a separable element which may preferably be formed of molded plastic, sheet metal, or glass, but which may be alternatively formed of disposable material such as waxed cardboard or the like. Preferably, but not necessarily, the receptacle 14 will be formed of disposable material and will be separable with respect to the nozzle 16. Alternatively, the nozzle 16 and the receptacle 14 may be integral, and formed of any suitable material.

No matter which of the above forms is taken by the container 12, the nozzle portion will be formed to provide an open mouth defined by substantially horizontal, generally parallel lip portions 17 and 18 joined at 19, said substantially horizontal portions 17 and 18 merging, through smooth curves, with substantially vertical, parallel lip portions 20 and 21. In a preferred form of the invention, the horizontal length of the lip portions 17 and 18 will be approximately one inch, and the vertical length of the lip portions 20 and 21 will be approximately seven inches,

said lip portions being spaced apart approximately two inches. The horizontal distance from the point 19 to the rear wall 22 of the nozzle will be approximately three and one-half inches.

Preferably, but not necessarily, the upper ends of the lip portions 20 and 21 will be inturned as at 23 and 24 to round off the upper end of the nozzle 16; and we presently prefer to leave the upper ends of the lateral walls of the nozzle separated to provide an opening 25 to facilitate a poured douche or the administration of an enema with the bed pan in use position.

At its lower end, the nozzle 16 is formed to provide a continuous base portion or collar 26.

The receptacle 14 is formed to provide an open, upwardly-directed mouth 27 proportioned and designed to receive snugly the base portion 26 of the nozzle 16 in telescoped relation; and we presently prefer to support the container 12 by means of a spring clip 28 adapted to embrace the container in that region of the receptacle which is reinforced by the reception therein of the base 26 of the nozzle. Thus, the spring clip performs the dual function of clamping the receptacle 14 and the nozzle 16 in assembled relation, and supporting the assembly. Preferably, the clip 28 will comprise resiliently separable fingers whose free ends are spaced apart, and resiliently movable toward and away from each other, in a direction substantially parallel with the minor rim portions 17 and 18. That arrangement permits lateral withdrawal of the container 12 from the grip of the clip 28, by movement of the container in a direction transverse to the length of the bed with which it is associated, after the actuating means 15 has been operated to depress the container, removing it from the opening 11.

The spring clip 28 is supported upon a metal strap 29 which, in turn, is suitably supported upon the actuating means 15.

The lateral width of the pelvic floor of the average human trunk is approximately two inches. Therefore, with the patient's legs 30 and 31 in relaxed and substantially parallel position, the nozzle 16 can be projected upwardly between the inner surfaces 32 and 33 of the patient's legs in the manner clearly illustrated in Figs. 1 and 2; and, if the patient is in proper position relative to the opening 11, the major lip portions 20 and 21 will lie in contact with the pelvic floor 13 substantially at the lateral extremities of the floor. The length of the pelvic floor of the average human trunk, in a frontal-dorsal direction, is substantially six inches. Thus, with the nozzle 16 in use position, wherein the point of merger 19 between the lip portions 17 and 18 is substantially in contact with the dorsal portion of the base of the patient's trunk, the upper end of the nozzle will project slightly above the upper surfaces of the patient's legs. It will be seen that, with the bed pan in use position, the termini of the evacuation passages of the body are disposed within the mouth of the nozzle, but effectively guarded by the lip portions 17, 18, 20, and 21. At the same time, since the forward ends of the lip portions 17 and 18 are curved sharply inwardly to join at the point 19, even though those lip portions may be in contact with the dorsal portion 34 of the base of the trunk, substantially no pressure is exerted thereby against the patient, since the patient is supported by the swelling portions of the buttocks 35 upon the region 36 of the mattress immediately adjacent the opening 11.

In Figs. 6 and 7 we have shown another form of

container comprising an outer receptacle 40 adapted to be supported upon actuating mechanism 15 through the medium of a swivelling bracket 41, and an inner receptacle 42 having a nozzle portion 43. The nozzle portion 43 is provided with an open mouth defined by minor lip portions 44 and 45 merging at 46, and joined, through smooth curves, with major lip portions 47 and 48. In this form of the invention, the walls defining the lip portions 47 and 48 taper toward each other and join in a nose 49 in the manner more fully described in our co-pending application Serial No. 62,112, filed November 26, 1948 for Bed Pan Device. The lip portions 44, 45, 46, 47 and 48, in this form of the invention, are similar in character to the corresponding portions 17, 18, 19, 20 and 21 of the form of invention illustrated in Figs. 1 to 5, though the proportioning is somewhat different, whereby the projection of the lip portions 44 and 45 along the dorsal portion of the patient's trunk is somewhat longer. Also, in this form of the invention, the upper end of the nozzle is closed for a reason which is not pertinent to the present invention, so that the administration of enemas and douches is somewhat less convenient with this form of the invention. The manner of cooperation of the bed pan of Figs. 6 and 7 with the pelvic region of the patient's trunk, however, is substantially similar to that of the form illustrated in Figs. 1 to 5.

We claim as our invention:

1. The combination with a bed pan comprising a container having an open mouth bounded by generally parallel rims, said rims having portions laterally spaced apart a distance substantially equal to the normal width of the pelvic floor of a human body and being substantially vertically disposed, said rims further having portions merging with said first-named portions through smooth curves and substantially horizontally disposed, said last-named portions substantially conforming to the dorsal portion of the base of a human trunk when said first-named portions lie in contact with the pelvic floor of such trunk, of support means for said bed pan comprising a spring clip having resiliently separable fingers cooperatively supportingly embracing the body of said container below said rims.

2. The combination of claim 1 in which said fingers are provided with spaced tips free to move resiliently away from each other upon a line substantially parallel with said horizontally disposed rim portions.

3. A bed pan comprising a container including a receptacle portion and a nozzle portion, said receptacle portion being of substantially uniform horizontal section from top to bottom, the lateral dimension of such section substantially corresponding to the normal width of the pelvic floor of a human body and the dimension of such section from front to rear exceeding said lateral dimension, said receptacle portion being closed at its bottom, the over-all length of said container exceeding the thickness of a conventional bed mattress and springs increased by a dimension at least equal to the normal frontal-dorsal length of such pelvic floor, and the front of said nozzle portion being open from the upper end thereof and curving outwardly toward the front where it converges with the top of the receptacle portion.

4. A bed pan comprising a vertically elongated container of substantially uniform, sub-

stantially elliptical cross-section from end to end thereof, except that the front wall and adjacent regions of the lateral wall of said container are cut away from a point near the top of said container toward the bottom thereof a distance at least equal to the normal frontal-dorsal length of such pelvic floor to define a nozzle portion and to permit projection of a dorsal portion of the base of a human trunk into said container through the front of said container, the minor diameter of said container cross section extending between lateral walls of said receptacle and being substantially equal to the normal width of the pelvic floor of a human body, and the length of said container below the lower end of said nozzle portion being at least equal to the conventional thickness of a bed mattress and spring, the lower end of said receptacle being closed.

5. In a bed pan, in combination, a receptacle having an open mouth, a nozzle having one end telescopically associated with the mouth of said receptacle, said nozzle being provided, adjacent its opposite end, with an opening bounded by generally parallel rims, said rims having portions laterally spaced apart a distance substantially equal to the normal width of the pelvic floor of a human body and being substantially vertically disposed, said rims further having portions merging with said first-named portions through smooth curves and substantially horizontally disposed, said last-named portions substantially conforming to the dorsal portion of the base of a human trunk when said first-named portions lie in contact with the pelvic floor of such trunk, and support means for said receptacle and nozzle assembly, said support means including means resiliently engaging said assembly in the region of telescopic association between said receptacle and said nozzle.

6. In a bed pan, in combination, a receptacle formed of flexible material and having an open mouth, a nozzle having a generally tubular, rigid base telescopically received in the mouth of said

receptacle, said nozzle being provided, adjacent its opposite end, with an opening bounded by generally parallel rims, said rims having portions laterally spaced apart a distance substantially equal to the normal width of the pelvic floor of a human body and being substantially vertically disposed, said rims further having portions merging with said first-named portions through smooth curves and substantially horizontally disposed, said last-named portions substantially conforming to the dorsal portion of the base of a human trunk when said first-named portions lie in contact with the pelvic floor of such trunk, and support means for said receptacle and nozzle assembly, said support means including means resiliently embracing said receptacle in the region thereof in which said nozzle base is received to secure said receptacle and nozzle against separation.
